UNITED STATES PATENT OFFICE.

WILLIAM HUCKS, OF LONDON, ENGLAND.

METHOD OF AND APPARATUS FOR AERATING BEVERAGES.

SPECIFICATION forming part of Letters Patent No. 476,645, dated June 7, 1892.

Application filed August 6, 1891. Serial No. 401,853. (No model.)

To all whom it may concern:

Be it known that I, WILLIAM HUCKS, engineer, a subject of the Queen of Great Britain and Ireland, and a resident of 22 Oval Road,

5 Camden Town, London, in the county of Middlesex, England, have invented a Method of and Apparatus for Aerating Beverages for Immediate Consumption, of which the following is a specification.

10 The object of my invention is to provide means by which liquids of any kind—such as water, wine, beer, or the like—can be aerated in glasses or like receptacles (but I will refer to them as "glasses") in convenient quantity for immediate consumption.

15 According to my invention I provide a container or holder in which the glass containing the liquid to be aerated is placed so that the edge of the glass can be forced against a

20 seating to close it while the gas for aeration is admitted, and into which container or holder fluid under pressure corresponding to that to which the inside of the glass is subjected may be admitted to facilitate the making of a tight closure of the glass.

25 I preferably provide an elastic envelope in the said container, into which envelope the glass is placed, the fluid under pressure being admitted into the space in the container outside

30 the elastic envelope. I also provide means whereby gas under pressure can be passed into the liquid in the glass so closed, the said means preferably consisting of a ram or displacer, which is employed to displace the liquid in the glass, so that if not already full it is caused to rise to or nearly to the edge of the glass. The edge of the glass is then forced tightly against the seating to close it. The gas is then passed into the liquor in the glass

35 to aerate it. In order to enable the parts to be easily operated, I may provide means whereby the fluid under pressure is caused to act as a counter-balance on each side of the moving parts.

40 The general nature of the invention will be understood most readily if I first describe a simple form of the apparatus, after which I will describe the form of the apparatus which I consider best for practical use.

45 Figures 1 and 2 are vertical sections of the upper and lower parts of the simple form of apparatus which I will first describe, Fig. 1

presenting the parts in the position before they are brought into action for effecting the aeration, and Fig. 2 showing the parts in the 55 position into which they are brought for effecting aeration. Fig. 3 is a front elevation partly in section; Fig. 4, a vertical section as seen at right angles to Fig. 3; and Fig. 5 is a plan of the body part of the preferred practical form of the apparatus as hereinafter described. Fig. 6 represents the valvular arrangement hereinafter described, drawn to a larger scale. Fig. 6^a shows an arrangement for closing certain valves.

60 Referring first to Figs. 1 and 2, A represents a glass placed inside an envelope B of india-rubber or other suitable elastic material, attached to the metal cup C, being pinched against the said cup by the screwed-down 65 ring c.

65 c² is a space between the outside of the envelope B and the inside of the cup C, which space communicates by the pipe D with the gland-box E, supplied by the pipe F (furnished with a stop-cock f) with water under pressure sufficient to fill the annular space c². The cup C is raised or lowered by the wheel G, which is secured to the screw-nut g, mounted so as to be capable of rotating in the bracket 70 g², so that when the wheel G is rotated it actuates the pipe or stem D of the cup C by reason of the nut g engaging with the screw in the pipe or stem D. By this means the cup C can be brought up into position under the 75 ram or displacer H and sufficient pressure be exerted to form a tight closure of the mouth of the glass A by the rim thereof bearing against the elastic seating h. The ram or displacer H is actuated in a similar manner to 80 the cup C by means of the wheel h', secured to the screw-nut h², mounted so as to be capable of rotating in the bracket h³, the said nut h² engaging with the screw formed on the outside of the ram H. This ram H passes through 85 a gland h⁴, carried by the bracket h⁵, and is fitted with a tube J, which passes through a gland K and is extended into the gland-box L, furnished with a pipe M and stop-cock m, by which the gas is admitted for the purpose 90 of aerating.

95 To aerate any liquid required for consumption, the glass A should be about half-filled with the liquid to be aerated. The mouth of

the glass is then held near to the seating h and the ram or displacer H lowered into the said glass until the liquid therein is raised to the level of the rim of the glass, the air in the 5 glass meanwhile escaping between the rim of the glass and the packing h . Having so adjusted the displacer H , the glass containing the liquid is inserted into the envelope B and the cup C is raised by means of the hand-wheel G , so as to force the rim of the glass and also the edge c^3 of the ring c tightly against the seating h . The stop-cock f is then opened to allow the pressure of the fluid admitted thereby to force the rubber envelope B round 10 the glass at every point. The stop-cock f is then closed and the tube J is depressed (by a lever or other suitable means) to or near to the bottom of the glass. The stop-cock m is then opened, and then the gas will pass through 15 the tube J , making its exit through the small holes at the point j . The ram H is then gradually raised, and this will cause the gas which is entering at the point j to pass through the liquid. After the ram H has been raised to 20 its full extent the pipe J is raised out of the liquid nearly to the top of the gland-box L , and the ram or displacer is lowered again, so that the gas is forced out of the glass by the pipe J back to the stop-cock m . The stop- 25 cock m is then shut, the cup C is lowered, and the glass is removed, when the contents of the glass will be found to be aerated.

By this apparatus I can fill a glass with aerated liquid from a reservoir. I can construct this reservoir of glass and enable it to withstand the pressure of the gas by surrounding it with fluid under pressure, as described with reference to the glass A . The ram or displacer H by removing the air from the glass 30 will prevent frothing when drawing aerated liquid from a reservoir.

I will now proceed to describe the apparatus shown in Figs. 3, 4, 5, 6, and 6^a.

As in Figs. 1 and 2, A represents the glass placed inside an envelope B , of india-rubber or any other suitable material, attached to the metal cup C , leaving the space c^2 between the outside of the rubber envelope B and the inside of the cup C , this space communicating by the pipe D with the gland-box E , which is furnished with a pipe F , connected with the gas-chamber L . The cup C in this arrangement, instead of being actuated by a screw, is actuated by a pedal attachment to 45 the lever N , allowing the cup and pipe D to be raised and lowered sufficiently to introduce the glass A into the india-rubber envelope B and bring the glass with its mouth seated against the india-rubber ring h .

60 L is a chamber supplied through the inlet M with gas at a suitable pressure, the said gas filling the upper portion of the vessel L to the water-line w . The bottom of this chamber L is fitted with a double valve l and l^2 , 65 the inner valve l^2 having a spindle extending to the cap of the tube L^2 , carrying the valve l and working over a tube L^3 , secured to the

casting forming the bottom of the chamber L . When the valve l^2 is raised, it opens communication for gas from the chamber L 70 through the perforations l^3 into the interior of the tubes L^2 and L^3 , and thence by the passage p^3 and back-pressure valve p through the passage p^4 into the glass A . These and other details are shown more clearly in the 75 larger - scale drawing Fig. 6. When the mouth of the glass A is forced into position against the ring h , the projection Q from the cup C then presses on the spindle l^4 to raise it and open the valve l^2 . The outer valve l 80 is for opening and closing communication between the chamber L and the passage R , which leads by the passage s into the chamber S and also communicates with the pipe F . When the arm Q raises the valve l^2 , the valve l 85 is also raised by reason of the spindle of the valve l^2 raising the tube L^2 over the tube L^3 , the gas above the water-line w then passing, as aforesaid, from the gas-chamber L through the perforations l^3 down the tubes 90 L^2 and L^3 , through the valve l^2 and passage p^3 , valve p , and passage p^4 into the glass A , the water from L flowing through the valve C and passage R into the chamber S and by the passages s^2 into the hollow displacer H , so as to raise the pressure therein to the same pressure as that of the gas above the water-line w in the chamber L and effecting a counter-balance between the working parts of the apparatus. The arm Q also 100 acts on the spindle of the valve q , so as to close it, which will permit the water in L to communicate a like pressure to the water in the pipe F , this pressure passing by the box E and pipe D and forcing the cup C with further pressure against the seating h , and owing to the movable joint c^3 of the cup formed with the hydraulic ring, as shown, the cup C 105 will also be raised in its bottom part, and its top edge at c^4 , furnished with an elastic seating, will be closed against the projecting rim s^3 to further insure a tight closure, and thus it will be seen that when the glass A and cup C are raised, as described, there will be a hydraulic pressure outside the glass A equal to 110 the gas-pressure inside the glass, and there will also be a like hydraulic pressure in the chamber S . The displacer H is capable of longitudinal movement in the chamber S . h^6 is a hydraulic gland therefor. The displacer H is fitted with a fine perforated end H^5 , 115 similar to a garden-syringe, and is actuated by the hollow rod H^4 , passing through a gland in the cover of the chamber S and connected by the cross-head U' to the tube or rod U^5 , 120 which slides in the standard U^4 as a guide. H^3 is a plunger capable of sliding in the displacer H , the said plunger being operated by the tubular rod H^4 , passing through the tube H^2 and connected to the cross-head U 125 and communicating with the passage u therein. The cross-head U is also connected with the tubular guide U^2 , sliding through a gland in the standard U^3 . The rod H^4 can be drawn

up through the rod H^2 by a lever or other suitable arrangement, and it will then cause the piston H^3 to draw and force the liquid and gas through and from the perforated bottom H^5 of the displacer H.

5 The piston H^3 is provided with two valves x and y . The valve x , when opened by the downward movement of the piston, will allow gas to pass up the hollow rod H^4 through the passage u in the cross-head U, down the hollow guide-rod U^2 into the tubular standard U^3 , and by a passage at u^2 in the cover, as shown by dotted lines in Fig. 5, and by an orifice or pipe back into the chamber L. The valve y is dish shape and so light that the moment it is pressed upon by the liquid in the glass it will rise and close against its seat, preventing the flow of liquid into the hollow rod H^4 . If, however, any liquid should pass, it will be forced into the hollow standard U^3 and can be drawn off from time to time by the screw-valve u^3 , Fig. 3.

25 The rods H^2 and H^4 can be actuated together or separately by the connecting-rods z , attached to the cross-heads U and U' , so that the displacer H and piston H^3 may be moved up and down together or separately inside the chamber S.

30 The machine is prepared for use by filling the vessel S with water through a suitable inlet, the annular space c^2 in the cup C being also filled with liquid by the tube F; also the chamber L will be filled with water to the dotted line w . The liquid supply to all these 35 may be obtained from any suitable reservoir by the pipe Z. The chamber L will then be coupled by the inlet M to a suitable storage of the compressed gas to be used for aerating. The cup C will in starting the apparatus be 40 a sufficient distance from the seating h to permit the glass A to be introduced into the envelope B.

45 To aerate the liquid contained in the glass, which should be about half-full, the glass is first held with its mouth near to the ring h , and the plunger H and piston H^3 are then brought down together by means of the connecting-rods z into the liquid in the glass sufficiently to raise the liquid to the brim of the 50 glass. The glass with the liquid therein is then placed in the envelope B and the pedal is operated to raise the cup C, so as to bring the rim of the glass against the ring h , also forming a joint with the cup C, and the chamber S by the lower rim s^3 of the latter bearing against the rubber at c^4 . The action of 55 raising cup C will cause the arm Q to open the valves l and l' , at the same time closing the valve q . Thus an equilibrium of pressure will be established inside and outside the glass A, and also the pressure in the chamber S will be the same as that in the vessel L. Consequently the displacer H and piston H^3 can be actuated without any force beyond the 60 friction of the moving parts. The piston H^3 is now raised sufficiently to draw all the liquid out of the glass A into the displacer H,

and then the displacer and piston are together raised, lifting the liquid sufficiently high to allow of the gas entering by the passage p^4 to pass through the liquid drawn up into the displacer H, and the surplus gas thus drawn up may be forced out through the valves x and y up the hollow rod H^4 , and so pass to the chamber L as before described. 75 This operation may be repeated any number of times necessary to pass sufficient gas through the liquid to properly aerate it.

In order to expel all the gas not taken up by the liquid, the displacer H is returned to the 80 original position when liquid was displaced in the glass A. The piston H^3 is then lowered toward the perforated bottom H^5 of the displacer H, and any gas above the liquid will be forced through the valves x and y into the 85 hollow rod H^4 through the cross-head U, traversing the passage u , the hollow guide-rod U^2 , and standard U^3 and returning by the passage u^2 into the chamber L.

I claim as my invention—

1. The method of aerating liquids for immediate consumption in glasses, consisting in partially filling the glass with the liquid to be aerated, raising the level of the liquid in the glass by means of a hollow displacer, closing the glass air-tight, and forcing the gas through the displacer into the liquid while removing the displacer from the glass.

2. In an apparatus for aerating liquids, the combination of an elastic receptacle for the 100 glass for the liquid to be aerated with a cup surrounding the elastic receptacle, to which fluid under pressure is admitted, and means for closing the glass while the liquid is being aerated, substantially as set forth.

3. In an apparatus for aerating liquids, the combination of a receptacle for the glass with a ram or displacer for expelling air from the glass and means for closing the glass, all substantially as set forth.

4. In an apparatus for aerating liquids, the combination of a receptacle for the glass for the liquid and means for closing the glass with a displacer having a longitudinal movement to displace the liquid in the container 115 and a gas-inlet, all substantially as set forth.

5. In an apparatus for aerating liquids, the combination of a glass for the liquid and means for closing the same with two chambers L and S, a valved passage connecting the two chambers, a displacer for the liquid in the container, moving in the chamber S, and a valved passage leading from the chamber L to the glass, all substantially as and for the purposes set forth.

6. In an apparatus for aerating liquids, the combination of a glass for the liquid and means for supporting and closing the glass with a hollow ram or displacer having a perforated bottom and a gas-inlet, all substantially as set forth.

7. In an apparatus for aerating liquids, the combination of a glass for the liquid and means for supporting and closing the same,

with a hollow ram or displacer having a perforated bottom and a valved piston capable of longitudinal movement in the displacer, all substantially as and for the purposes set forth.

8. In an apparatus for aerating liquids, the combination of an elastic receptacle for the glass, a chamber surrounding the elastic receptacle, and means for admitting fluid under pressure to the said vessel with a hollow displacer and an inlet-passage provided with a cock to admit gas to the glass, all substantially as set forth.

9. In an apparatus for aerating liquids, the combination of an elastic receptacle for a glass and a vessel surrounding the elastic recepta-

cle with a chamber S, a movable displacer, a chamber L, valved passages from the said chamber L, one leading to the glass, one to the chamber S, and one to the vessel surrounding the elastic receptacle, and means for closing the glass, all substantially as set forth.

In testimony whereof I have signed my name to this specification in the presence of two subscribing witnesses.

WILLIAM HUCKS.
